AUTOMATIC FIREARM

Timothy F. Horan, New Haven, Conn., assignor to
Savage Arms Corporation, Utica, N. Y., a corporation of Delaware

Application July 30, 1940, Serial No. 348,429

5 Claims. (Cl. 42—3)

This invention relates to firearms, and more particularly to a firearm of the automatic type wherein the breech bolt is moved rearwardly in the receiver by the firing reaction, and returned to a forward position by spring action, the movement of the bolt serving to actuate mechanism to throw a fresh cartridge from the magazine of the gun into the chamber, so that at the end of the cycle of operations resultant upon the firing of the gun a fresh cartridge is in the chamber and the gun ready for a subsequent firing.

Some difficulty has at times been experienced with guns of this type in that, when the bolt has been blown rearwardly by the firing reaction and is returned by the spring provided for that purpose, the action takes place so quickly that sufficient time has not been allowed to permit the fresh cartridge to be moved to a position where it will be thrown into the chamber by the return of the bolt. This will cause the gun to 20 jam, and results in considerable inconvenience to the operator.

It is contemplated by the present invention temporarily to retard or delay the return of the bolt to breech-closing position, so that this return will not take place until the cartridge lifter has had sufficient time to operate and lift the fresh cartridge into a position in front of the chamber. In the embodiments of the invention shown, this retardation of the return of the bolt is effected by a detent which serves to delay the return of the bolt, and in some forms of the invention this detent is connected to the trigger, whereby when the trigger is pulled the detent will be permitted to move to a position to engage a part of the bolt when the latter is moved rearwardly, and this detent will hold the bolt in a rearward position until the trigger has been released. Upon release of the trigger the latter will be moved forwardly by the trigger spring, and the forward motion of the trigger will move the detent to disengaging position and permit the return of the bolt to breech-closing position by its spring. As in firearms of this type it is necessary for the user of the gun to release his finger pressure on the trigger between firing operations, it will be apparent that this will not result in any inconvenience to the user, nor will it interfere with the rapidity of the operation of the gun, in that immediately upon release of the trigger the bolt will be returned to breech-closing position.

One object of the invention is the provision of a firearm having a bolt mechanism of improved construction and operation.

Another object of the invention is to improve the action of the bolt mechanism of an automatic firearm.

A still further object of the invention is the provision of an automatic firearm having provision for retarding the return of the bolt to breech-closing position after the bolt has been moved rearwardly by the firing reaction.

10 A still further and more specific object of the invention is the provision of a firearm having a bolt mechanism moved rearwardly in the receiver by the firing reaction and returned to breech-closing position by a spring, the firearm being provided with a detent to delay the return of the bolt by the spring until time has been permitted for the transfer of a fresh cartridge into the chamber, and still more specifically to provide for the control of this detent by the actuation of the trigger.

15 Still other objects of the invention are the improvement of the mechanism for transferring a cartridge from the magazine to the chamber, for improving the striker and spring assembly which moves the striker forward when the trigger is pulled, and which returns the bolt to forward position, and to improve other parts of the bolt action of a firearm whereby this action will be positive and efficient and at the same time may be economically constructed.

20 To these and other ends the invention consists in the novel features and combinations of parts to be hereinafter described and claimed.

In the accompanying drawings:

25 Fig. 1 is a sectional view through the material portion of the mechanism of an automatic firearm;

Fig. 2 is a similar view showing the parts in another position;

30 Fig. 3 is a view similar to Fig. 1 showing a modified form of my invention;

Fig. 4 and 5 are views similar to Fig. 3 but showing different positions of the parts;

35 Fig. 6 is an exploded view of the striker and spring assembly shown in Fig. 1;

Fig. 7 is a detail elevational view of the throat member shown in Figs. 1 and 2;

Fig. 8 is a partial sectional view of a receiver and bolt mechanism showing a modified form of bolt-retarding mechanism; and

40 Fig. 9 is a view similar to Fig. 8 showing a further modification.

To illustrate one embodiment of my invention I have shown in Fig. 1 of the drawings an automatic firearm of the rifle type having a stock 10,

a barrel 11, receiver 12, and a magazine 11a mounted below the barrel.

The receiver, as is usual, is a hollow member, and reciprocably mounted therein is the bolt 13, the rear end of the receiver being closed by a plug or cap 14 provided with a socket 15 for a purpose to be hereinafter described.

The bolt 13 is provided with a longitudinal bore 16 which extends nearly to the front end of the bolt, the latter, however, being closed except for the small opening 17 through which is moved the firing pin 18, the latter being secured on the end of a striker 19 reciprocably mounted in the bore 16 of the bolt. This bolt is also provided with a longitudinally extending slot 20 opening downwardly through the lower portion thereof, and within this slot rides a lug 21 on the striker provided with a shoulder portion 22 designed to be engaged by the trigger sear, as will be herein-after described.

Toward its forward end the bolt is provided with cut-out or recessed portions 23 and 24 between which is a cam member or surface 25 which serves to operate the cartridge-lifting mechanism.

The receiver is open at its lower forward end, and communicates at this point with an upwardly facing opening in a throat member 26, the forward part of which extends into the magazine 11a, as shown at 27, and is there secured. The throat 26 is slotted longitudinally, and a lifter member 28 is pivoted to the receiver and is adapted to swing upwardly through this slot to raise a cartridge from the throat into position to be forced into the chamber in the barrel.

The lifter 28 is not only pivotally connected to the receiver, but is also allowed a limited bodily movement in a vertical direction. To this end a pin 29 is secured to the lifter 28, and this pin is movably mounted in slots 30 arranged upon each side wall of a lug 31, this lug being slotted longitudinally to permit the body portion of the lifter to pass therethrough. A spring 32 is provided below the member 28 to normally maintain the pin in raised position in the slots 30. The lifter 28 is also provided with a finger 32a to normally close the throat 26 against the entrance thereto of a shell from the magazine 11a when the lifter is in raised position.

The lifter is also provided with projecting fingers 33 and 34, these fingers extending upwardly into the receiver to be engaged by the cam surface 25. It will be apparent that when the bolt is moved rearwardly from the position shown in Fig. 1, the cam surface 25 will strike the finger 34 and throw the forward end of the lifter upwardly to force a cartridge from the throat into the receiver in position to be moved into the chamber. At this time, however, it will not be possible to move the cartridge upwardly to its final position, and for this reason the pivot pin 29 of the lifter is permitted to move downwardly, so that the finger 34 may be cammed to its lower-most position by the member 25, as shown in Fig. 2. When the cartridge has been moved forward slightly by the bolt and is free to move into the receiver, the spring 32 below the lifter moves the pin and the forward end of the lifter 28 upwardly, which throws the cartridge into the receiver in a position from which it is ready to move into the chamber.

The striker 19 is threadedly secured to the forward end of an elongated pin 31 having a head 38 upon its rear end. Surrounding this pin is a sleeve 39 having a sufficiently large opening for most of its length to pass over the head 38, the

opening in the sleeve being reduced at its forward end, however, as shown at 40, so that it will be retained upon the pin 31 at all times. As the striker is somewhat larger than the pin 31, a shoulder 41 is provided at the junction of these two parts, and between this shoulder and the forward end of the sleeve 39 is a compression spring 42 serving to urge the striker 19 forwardly to fire the gun. It may be here stated that the rear end of the sleeve 39 is supported by the bottom portion of the recess 15 in the cap 14.

Mounted upon the sleeve 39 and acting against the enlarged rear end 43 thereof is a second spring 44, which embraces the sleeve and also 15 embraces the spring 42. At its forward end the spring 44 is adapted to act against a shoulder 45 in the bore of the bolt 13, and this spring tends to maintain the bolt in the forward breech-closing position shown in Fig. 1. The springs 42 and 20 44 will preferably be wound in opposite directions so that the outer one will slide freely over the inner spring. It will be apparent that with this construction the striker 19, pin 31, sleeve 39 and associated springs may be removed from the bolt and will remain as an assembled structure, 25 due to the fact that the sleeve cannot be forced from the pin 31 by the springs. These parts may be readily disassembled and reassembled by virtue of the threaded connection between the pin 31 and the striker 19.

Secured to the rear portion of the receiver is a slotted lug 50 between the parts of which is mounted a trigger 51 upon the pivot pin 52, the forward end of the trigger being provided with 35 a sear 53 to engage the shoulder 22 on the striker 19 to retain the gun in cocked position, and to effect its release when desired. The trigger extends rearwardly of the pivot pin 52, and a spring 54 acts between the receiver and the rear end of the trigger to normally force the latter forwardly and urge the sear into position to engage the shoulder 22.

The rear portion of the trigger structure is recessed, as shown at 55, and in this recess is slidably mounted a detent 56, the movement of the detent being limited by a pin 57 secured to the trigger, which pin is received in a slot 58 provided in the detent 56. A spring 59 normally urges the detent to an outward or protracted position. The outer end of the detent is beveled, 45 as shown at 60, so that the detent may be cammed downwardly into the recess 55 by the rear end of the bolt 13 when the latter is moved to the rear portion of the receiver during the operation of the gun.

A short distance forwardly of its rear end the bolt is provided with a notch 61 within which the detent 56 is adapted to be engaged when the bolt has been thrown rearwardly, and when the trigger is in position to force the detent 56 into the receiver, as shown in Fig. 2.

It will be apparent that when the parts are in cocked position, as shown in Fig. 1, the detent 56 will not stand within the receiver, and will be clear of the bolt 16. However, when the trigger is pulled, in order to effect release of the shoulder 22 by the sear 53, the rear portion of the trigger is moved upwardly against the spring 54, thus moving the detent 56 to a position within the receiver, as shown in Fig. 2. When in this position of the parts the bolt is thrown rearwardly, the detent 56 will be cammed downwardly against the action of the spring 59 by the rear end of the bolt. As soon, however, as the notch 61 in the

bolt registers with the detent 56, the spring 59 will force the detent upwardly to engage the rear portion of the notch 61 and hold the bolt in retracted position, as shown in Fig. 2.

In this position of the parts, both of the springs 42 and 44 will be in compressed position, as the movement of the bolt will compress the outer spring against the shoulder 45, and as the striker is moved rearwardly with the bolt, the striker spring 42 will be compressed between the forward end of the sleeve 37 and the shoulder 41.

As long as the trigger is held rearwardly by the finger in the position in which the firearm is discharged, the bolt will be prevented from being moved forwardly to breech-closing position. As soon, however, as the trigger is released by the finger, it will be returned to its original position by the action of the spring 54. This movement of the trigger will move the detent downwardly to release the bolt, due to the pin and slot connection between the detent and the trigger, and at the same time the sear 53 will be moved upwardly to engage the shoulder 22 on the striker. Thus, while the bolt will immediately be moved to breech-closing position by its spring when the trigger is released, the striker will be retained in cocked position by the engagement therewith of the sear 53. This retardation of the return movement of the bolt during the time that the trigger is engaged by the finger will permit ample time to elapse for the lifter 23 to move the cartridge in position to be thrown into the chamber by the forward movement of the bolt, and there will be no tendency for the parts to jam.

In Figs. 3 to 5 of the drawings I have shown a form of my invention applied to a gun having firing mechanism of slightly different construction. In this instance the barrel of the gun is shown at 11, the receiver at 12, and the mechanism for throwing the cartridge into the chamber from the magazine may be the same as that described in connection with the form of my invention shown in Figs. 1 and 2.

In this instance the bolt, instead of being a single member, is divided into two portions, the front portion or bolt proper 75 and the rear portion or hammer 76. The front portion is provided with a slot 77 substantially T-shaped in cross section, and within this slot is slidably mounted a striker member 78 of similar shape carrying on its forward end the firing pin 79, which is adapted to strike a cartridge in the chamber through the usual opening 80 in the front portion of the bolt. The striker 78 is provided with a transversely extending head 81 at its rear end, which head seats in a circumferential slot 82 in the hammer 76, and it will be understood that the hammer is also longitudinally slotted, as at 83, to receive the body of the striker 78.

The hammer 76 is hollow, the opening therethrough being somewhat reduced at its forward end, as shown at 84, and extending through the hammer is a pin 85 provided with a head 86 against which is urged a washer 87 by a bolt spring 88 surrounding the pin 85 and reacting against a washer 89 secured at the opposite end of the pin and resting in the opening 15 of the cap 14, which closes the rear end of the receiver. Also surrounding the pin 85 and embracing the spring 88 is a second spring 90 wound in the direction opposite to that of the first spring, which second spring also reacts against the head or washer 89 at one end and against the reduced

portion 84 of the bore of the hammer 76 at the other end. It will be understood that the spring 88 tends to maintain the bolt in its forward position, as shown in Fig. 3, while the spring 90 tends to maintain the hammer in a forward position against the rear end of the bolt.

In Fig. 3 of the drawings the bolt is shown in its forward breech-closing position, but the hammer is in its rear or cocked position, being held in this position by the sear 91 of a trigger 92 pivoted at 93 to the lug 94 secured to the receiver, the trigger being urged by the spring 95 to a position in which the sear engages the hammer to hold the latter in its rear or cocked position. It will be understood that when the trigger is pulled, the sear 91 is moved downwardly, and the hammer 76 released. The hammer spring 90 then drives the hammer forwardly, and the hammer carries with it the striker 78 and firing pin 79, which strikes the shell in the chamber.

In order that the return of the bolt may also be delayed in this instance, after it has been thrown rearwardly by the firing reaction to permit sufficient time for the new cartridge to be moved into position to be thrown into the chamber, I have provided a detent to engage the bolt and hold it in rearward position until the trigger is released. This detent is shown at 97, and is provided with a slot 98 which loosely receives a pin 99, the pin passing through the walls of a slotted lug 100 secured to the receiver, through the slot of which the detent 97 extends. In order that the detent will be controlled by the action of the trigger, the forward portion of the latter is provided with a recess or socket 101 which slidably receives the rear end 102 of the detent. A compression spring 103, acting against the bottom of the recess, normally forces the detent outwardly or to the right with respect to the end of the trigger.

The lower portion of the bolt is provided with a notch or recess 104 within which is adapted to engage the pointed or hooked end 105 of the detent 97, when the latter is projected within the receiver through the opening 106, as shown in Fig. 4.

The operation of this form of my device will now be described. As the parts are shown in Fig. 3, the gun is cocked and ready to fire. It will be noted that the bolt is also provided with a recess 107, which, when the bolt is in full breech-closing position, will lie directly above the end 105 of the detent 97. This permits the end of the detent to enter that slot when the trigger is pulled, and if the breech bolt were not in full closed position and the slot did not register with the detent, as shown, for example, in Fig. 5, it would not be possible to pull the trigger.

When the trigger is pulled the hammer is moved forwardly by its spring, and when the cartridge is discharged both hammer and bolt are moved rearwardly to the position shown in Fig. 4 by the firing reaction. As the forward end of the trigger is pulled downwardly at this time, and as the rear portion of the bolt cams the end of the detent downwardly and rearwardly during the rearward motion of the bolt, the detent must be permitted a certain amount of longitudinal movement upon the pivot pin 99, as it would not otherwise be permitted to rock downwardly with the trigger in the position shown in Fig. 5. The provision of the slot 98 allows this movement, as shown in Fig. 5, so that the detent member 97 can move downwardly and rearwardly, and thus

permit the bolt to pass. As soon as the notch 104 in the bolt arrives opposite the end 105 of the detent 97, the spring 103 moves the detent member 97 forwardly and upwardly, according to the movement permitted by the slot 98, and effects engagement of the detent portion 105 in the slot 104 of the bolt, as shown, for example, in Fig. 4 of the drawings. The bolt is, therefore, held in a rearward position and will not be allowed to move forwardly by its spring until the trigger is released to move the detent from engagement with the bolt. Upon release of the trigger the forward end of the trigger is moved upwardly by the spring 95, and the sear 91 is engaged in front of the hammer to hold it in a rearward position at the same time that the detent 105 is moved downwardly to permit the bolt to be moved to forward position. This arrangement provides for the retarding of the forward movement of the bolt until ample time has been allowed to permit a new cartridge to be thrown into position to enter the chamber.

In Figs. 8 and 9 of the drawings I have shown some modified forms of my invention with respect to the retarding of the return of the breech bolt. As shown in Fig. 8, the bolt 13, disposed in the receiver 12, is provided adjacent its rear end with a recess 110 having a beveled end surface 111. Pivoted to the receiver at 112 is a detent 113 having a correspondingly beveled end 114. The detent 113 is provided with a tail portion 115 against which acts a compression spring 116 the other end of which bears against a portion of the receiver.

It will be apparent that the spring 116 will tend to maintain the detent in its upper position shown in Fig. 8, although it will permit the detent to be cammed downwardly by the bolt upon its rearward movement. When the bolt reaches the position shown in Fig. 8, the detent will be forced upwardly by the spring, and the beveled end 114 will engage the beveled surface 111 of the recess 110, and momentarily retard the return of the bolt under action of the bolt spring. It will be understood that the angles of the beveled surfaces 111 and 114 are not such that the bolt will be maintained in its rearward position by the detent, but the angles of these surfaces are only sufficiently steep to momentarily retard the bolt and then permit it to slip by under the action of its spring, and by camming the detent downwardly return to closed position. I have found that an angle of approximately 30° is suitable for this purpose.

In Fig. 9 of the drawings the bolt 13 is provided with a recess 120 within which is disposed a detent 121 pivoted to the bolt at 122. A compression spring 123 normally maintains the detent in its lower position, where its beveled surface 124 will engage the beveled surface 125 at the end of a recess 126 formed in the wall of the receiver. In this instance when the bolt is thrown rearwardly by the firing reaction, the detent will drop downwardly until it catches in the recess 126, and the return of the bolt will be momentarily retarded until the beveled surface 124 slips up to free itself from the beveled surface 125 and permit the return of the bolt under the action of its spring.

While I have shown and described some preferred embodiments of my invention, it will be understood that it is not to be limited to all of the details shown, but is capable of modification and variation within the spirit of the invention and within the scope of the appended claims.

What I claim is:

1. A firearm comprising a receiver, a trigger, a breech bolt reciprocably mounted in the receiver and adapted to be moved rearwardly by the firing reaction, a spring to return said bolt to its forward position, said bolt being provided with a shoulder, a detent adapted to engage said shoulder and prevent the return of the bolt, means connecting said detent to the receiver for pivotal and longitudinal movements, an end portion of said detent being connected to the trigger for movement by the latter to position to disengage said shoulder, a striker, and a second detent to control said striker, said second detent being actuated by the trigger.

2. A firearm comprising a receiver, a trigger, a breech bolt reciprocably mounted in the receiver and adapted to be moved rearwardly by the firing reaction, a spring to return said bolt to its forward position, said bolt being provided with a shoulder, a detent member having an end portion adapted to engage said shoulder, said detent being connected to the receiver by a pin and slot connection, said trigger being provided with a recess, and the other end portion of said detent member being received in said recess whereby said other end portion is moved relatively to the receiver by movement of the trigger, a striker, a second detent controlling said striker, and said second detent being operatively connected to said trigger to be controlled thereby.

3. A firearm comprising a receiver, a trigger, a breech bolt reciprocably mounted in the receiver and adapted to be moved rearwardly by the firing reaction, a spring to return said bolt to its forward position, said bolt being provided with a shoulder, a detent member having an end portion adapted to engage said shoulder, said detent being pivotally connected to the receiver by a pin and slot connection, said trigger being provided with a recess, the other end portion of said detent member being received in said recess whereby said other end portion is moved relatively to the receiver by movement of the trigger, and a spring in said recess tending to maintain said pin at one end of said slot, a striker, a second detent controlling said striker, and said second detent being operatively connected to the trigger to be actuated thereby.

4. A firearm comprising a receiver, a breech bolt slidably mounted therein and driven back by the recoil of the gun, said bolt having a forwardly directed detent face, a spring to return said breech bolt to its forward position, a detent member pivotally connected to the receiver having a forward end portion adapted to engage said face when the rear end of said member is depressed, said pivotal connection also permitting longitudinal movement of said member, a trigger pivotally carried by the receiver and having an arm projecting forwardly of its pivot, the rear end of said detent member being engaged by said arm whereby the former is depressed when the trigger is pulled, spring means urging said member forwardly with respect to its pivot, a hammer disposed rearwardly of said breech bolt and carried rearwardly thereby, said hammer having a holding face, a cocking sear carried by the trigger and adapted to engage said holding face when the hammer is in its rearward position, and a trigger spring urging said sear toward engaging position.

5. A firearm comprising a receiver, a breech bolt slidably mounted therein and driven back by the recoil of the gun, said bolt having a for-

wardly directed detent face, a spring to return said breech bolt to its forward position, a detent member pivotally connected to the receiver having a forward end portion adapted to engage said face when the rear end of said member is depressed, said pivotal connection also permitting longitudinal movement of said member, a trigger pivotally carried by the receiver and having an arm projecting forwardly of its pivot, a socket in the forward end of said arm, the rear end of said detent member being engaged in said socket

5 to be depressed when the trigger is pulled, a spring in the socket urging said member forwardly, a hammer disposed rearwardly of said breech bolt and carried rearwardly thereby, said hammer having a holding face, a cocking sear carried by the trigger and adapted to engage said holding face when the hammer is in its rearward position, and a trigger spring urging said sear toward engaging position.

10

TIMOTHY F. HORAN.
